CLAIM

We claim the ornamental design for a matchbox shaped scale, as shown and described.

DESCRIPTION

FIG. 1 is a top perspective view of a matchbox shaped scale according to the new design, with the outer cover partially covering the inner piece.

FIG. 2 is a top perspective view of the inner piece.

FIG. 3 is a top view of the inner piece.

FIG. 4 is a bottom view of the inner piece.

FIG. 5 is a front side view of the inner piece.

FIG. 6 is a right side view of the inner piece.

FIG. 7 is a perspective view of the cover.

FIG. 8 is a top view of the cover.

FIG. 9 is a bottom view of the cover.

FIG. 10 is a side view of the matchbox shaped scale, with the inner piece completely inside the cover; and,

FIG. 11 is a top perspective view of the matchbox shaped scale, with the inner piece completely inside the cover.

The broken lines are shown for illustrative purposes only and form no part of the claimed design.
